DECORATIVE BAG

Anna Dennis, Hopkins, Minn.

Application October 7, 1937, Serial No. 167,821

1 Claim. (Cl. 150—52)

This invention relates to an article of manufacture having the outward appearance of a doll and being provided with a bag adapted to receive and conceal other articles.

5 An object of this invention is to provide an article of manufacture in the form of a bag having the outward appearance of a doll and adapted to be opened on the front thereof to receive various articles to be temporarily stored out of view.

10 Another object of this invention is to provide an article of manufacture in the form of a bag having the outward appearance of a doll, said bag having an inside lining of rubberized or oiled silk to make it waterproof and being adapted to be 15 opened sufficiently so that articles to be stored out of view may be placed into said bag.

Still another object of this invention is to provide an article of manufacture adapted to be used as a bag for storing or carrying rubber articles 20 which may be hung into said bag while damp or wet, said bag being so constructed that moisture will not penetrate it when used under normal conditions.

Other and further objects of this invention will 25 be apparent to those skilled in the art to which it relates from the following specification and claim.

In accordance with the invention I provide a 30 bag adapted for storing or carrying rubber articles of various kinds without necessitating first thoroughly drying said articles. The device of my invention is made to appear like a large doll and is provided with a decorative outer covering which is placed over an inner substantially waterproof lining. The outer covering and lining are assembled in such a manner that they 35 may be opened conveniently and simultaneously so that the article to be placed inside may be hung upon a suitable support attached to the lower portion of the doll head frame which projects into the top part of the bag.

The bag is made to be opened on the front although this opening may be provided to the back if desired. A suitable "zipper" type fastener 40 is used to close the opening to prevent dust and germs from entering the bag.

Other details of my invention are described and illustrated in the specification and drawings.

Referring to the drawings briefly, Fig. 1 is a 50 front view of the bag of my invention; Fig. 2 is a sectional view showing details of construction of the bag; Fig. 3 is a sectional view showing details of construction of the bag and the manner in which articles may be supported therein; and Fig. 4 is another sectional view showing further

details of construction of the bag and the manner in which it is attached to the neck of the doll head.

Reference numeral 10 designates the outer decorative covering of the bag which may be 5 made of any material such as cotton, rayon, wool, paper, silk or the like and a suitable design or pictures may be printed thereon, woven therein or otherwise registered on this decorative covering. The bag, having the outer covering 10, is 10 provided with a "zipper" type fastener 11 having a slideable member 12 adapted to open or close the "zipper" fastener. This fastener preferably extends to within a short distance of the bottom of the bag to prevent water which may 15 have accumulated in the bottom of the waterproof bag liner 19 from leaking or dripping out through the fastener hooks upon the outside cover 10 when the bag is being supported by the ribbon or band 14. A ring 13 is attached to the 20 bottom of the outer cover 10 to serve as a finger grip when the fastener member 12 is being pulled upward from a lower position.

The top of the bag is collected into a series of ruffles 15 and tied around the neck of the doll 25 head 16 by means of the ribbon 17.

The bag is provided with an inner layer or lining 19 of material, such as rubberized silk or oiled silk which is well adapted to retain its shape. This lining is formed into a bag by taking an 30 elongated strip of material and folding it in the middle so that the fold corresponds to the bottom. The sides 23 and 23a are then placed one over the other so that they lap over each other a short distance and they are glued by a suitable waterproof 35 cement, into place. The same is done with the edges 24 and 24a. The bottom of the lining 19 is thus formed without a seam to eliminate the possibility of leaks in the bottom of the lining. The side edges of the covering 10 are turned in and 40 sewed together as shown at 18.

As a result of the triangular construction of the bag and the gathering of the top portion around the neck 26, the bottom of the bag becomes centrally bowed. This is an advantage because water dripping from the rubber bathroom articles collects in this bowed imperforate portion and does not drip to the bathroom floor.

Various ways of constructing the lining 19 and the cover 10 may, of course, be employed and 50 where the lining 19 is made of thin rubber it is possible to make it without the side seams by using the proper shape forms which are dipped into a suitable latex bath, for example.

The "zipper" fastener 11 is attached to the in- 55

ner lining 19 and outer cover 10 by sewing the cloth strip 21 to which the hooks of the fastener are attached, to the folded edges 22 of the aforesaid lining and cover. It is, of course, obvious that 5 the hooks of the fastener 11 may be attached to the edges of the lining and cover direct if desired without first attaching them to the strip 21.

In Figs. 3 and 4 I have illustrated the manner 10 in which a rubber article 30, having an apertured portion 31 and a rubber tube 32 may be supported on the hook 28 inside of the bag. The hook 28 is riveted to the lower back portion 28 of the doll. This back portion 28 and the front portion 27 are employed for the purpose of spreading the top 15 part of the bag to prevent the bag from collapsing. The doll head may be made hollow and the mouth provided with a slight aperture to permit air to circulate through the bag to a slight degree.

It will be observed that I have attached the 20 ring 13 to the outer cover 10 without cutting the lining 19 to prevent water from leading out around this ring as probably would be the case if the lining 19 were cut.

I have also provided a band 25 around the doll's 25 neck. The support 14 is attached to this band and the band may or may not be attached to the bag. The bag is held around the doll's neck by the ribbon 17 as shown.

While I have described and illustrated this invention in considerable detail it is to be understood that I do not desire to limit the invention to the exact details described and illustrated except in so far as those details may be set forth in the claim.

35 What I claim and desire to secure by Letters Patent is as follows:

An article of manufacture comprising a substantially triangularly shaped bag-like cover adapted to be supported vertically from one of the corners thereof for receiving and concealing rubber and like bathroom articles, a frame member 5 positioned in the top corner of said bag-like cover, said bag-like cover being formed of one piece of material and having a shape retaining substantially waterproof lining substantially permanently joined on the sides and folded back upon itself at 10 the base, the top part of said bag-like cover being collected around said frame member whereby said base forms a downwardly bowed imperforate bottom for the purpose of collecting water dripping from the bathroom article, said bag-like cover 15 having an elongated centrally disposed generally vertical opening in the front thereof extending from a point adjacent to the top thereof to a point near but not down to the bowed bottom whereby bathroom articles may be inserted therein and removed therefrom without danger of water collected in said bowed bottom spilling out, fastener means for closing said opening, means for holding the portion of said bag-like cover surrounding said frame member decoratively collected into a series 25 of ruffles, means attached to said frame member for supporting the bathroom article inserted into said bag-like cover, and supporting means attached to said bag-like cover at the upper portion of said frame member so that the bag-like cover 30 may be hung with its opening substantially vertical to prevent water collected therein from dripping therefrom.

ANNA DENNIS. 35
